United States Patent Office

Des. 201,538
Patented June 29, 1965

201,538

HAMMER

William C. Willis, Bellflower, Calif. (820 Edison Bldg.,
100 Long Beach Blvd., Long Beach 2, Calif.)

Filed June 19, 1962, Ser. No. 70,602

Term of patent 14 years

(Cl. D94—4)

FIGURE 1 is a side elevational view of a hammer showing the present design;

FIGURE 2 is an elevational view of the other side thereof;

FIGURE 3 is a front elevational view thereof;

FIGURE 4 is a rear elevational view thereof;

FIGURE 5 is a top plan view thereof; and

FIGURE 6 is a bottom view thereof.

The characteristic feature of my design resides in the configuration of the hammer head as shown.

I claim:

The ornamental design for a hammer, substantially as shown and described.
